United States Patent Office

Des. 213,111
Patented Jan. 7, 1969

213,111

BATTERY CHARGER

Daniel L. Jaffe, Bethesda, Md., assignor to Technological
Products, Inc., Rockville, Md.

Filed Mar. 20, 1968, Ser. No. 11,068

Term of patent 14 years

U.S. Cl. D26—15
Int. Cl. D13—02

FIG1

FIG2

FIG7

FIG8

FIG. 3

FIG. 4

FIG. 5

FIG. 6

FIG. 1 is a perspective view of a battery charger showing my new design;

FIG. 2 is a side elevational view thereof;

FIG. 3 is a top plan view thereof;

FIG. 4 is a bottom plan view thereof;

FIG. 5 is an end elevational view from left to right of FIG. 2 looking into the contact elements;

FIG. 6 is an end elevational view from right to left of FIG. 2;

FIG. 7 shows a cross-section taken on line 7—7 of FIG. 3; and

FIG. 8 is a cross-sectional view on line 8—8 of FIG. 2.

The dominant features of my design reside in the portions shown in full lines.

I claim:

The ornamental design for a battery charger, as shown and described.
